UNITED STATES PATENT OFFICE.

WILLARD E. PLAYTER, OF COLLINSVILLE, ILLINOIS.

BAG-CLEANING APPARATUS.

1,118,044.

Specification of Letters Patent. Patented Nov. 24, 1914.

Application filed February 19, 1914. Serial No. 819,818.

To all whom it may concern:

Be it known that I, WILLARD E. PLAYTER, a citizen of the United States of America, residing at Collinsville, Madison county, 5 State of Illinois, have invented a certain new and useful Bag-Cleaning Apparatus, of which the following is such a full, clear, and exact description as will enable any one skilled in the art to which it appertains to 10 make and use the same, reference being had to the accompanying drawings, forming part of this specification.

My invention relates to improved means for removing the fine particles of material 15 from the fabric of bags which have been used as containers for flour, cement and the like, or which act as strainers for removing suspended solids from gases, such as in smelting plants for example.

20 It is the object of my invention to produce pneumatically operated bag cleaning means which will be simple and efficient and which will not only dislodge the material adhering to and collected in the bag fabric, 25 but will also facilitate the removal of the material from the interior of the bag and its collection in a suitable container.

In the accompanying drawings, which 30 illustrate one embodiment of my invention, Figure 1 is a view partly in section and partly in elevation, showing my improved bag cleaning apparatus; and Fig. 2 is a view of a portion of a bag house such as used in smelting plants, and illustrates one commercial application of the bag cleaning apparatus of Fig. 1.

The bag cleaning apparatus comprises a flexible tube 2, suitably suspended within the bag to be cleaned, and having one end 40 free to vibrate. I prefer to connect this tube with a suitable air or fluid reservoir 1 around which the bag 3 may be positioned, being held in place by any convenient means such as a string or wire 5. The lower end 45 of the bag is preferably positioned around a suitable thimble 4 communicating with a material collecting chamber. Air or other suitable fluid, under pressure, is supplied to the reservoir 1 and, through it, to the flexible tube or beater 2, by means of the pipe 6. The reactions resulting from air rushing through the tube 2 cause it to vibrate with considerable violence and strike the walls of the bag, thereby dislodging the collected 55 material therefrom. The current of air from the end of the tube passes downward

carrying the dislodged material with it. When the supply of air is cut off, the air under pressure in the reservoir 1 supplies a relatively slow and gentle current of air 60 to the interior of the bag for a short time after the tube 2 has ceased to vibrate, with the result that practically all of the dislodged material is carried out of the interior of the bag. While air is flowing 65 downwardly from the tube 2, it, of course, tends to create a vacuum in the upper part of the bag and, therefore, to draw air through the upper part of the walls of the bag; and thus downward currents of air 70 are established throughout the whole interior to carry out the dislodged material.

It will be apparent from the foregoing description that bags of any kind can be readily attached to the apparatus and quickly 75 and thoroughly cleaned.

In the application of my invention to the bag houses of smelting plants and the like, as illustrated in Fig. 2, each bag 3 is provided with the apparatus shown in Fig. 1 80 and any suitable number of these bags may be in communication with a single pipe 6 controlled by the valve 7 and cleaned simultaneously, the dislodged material flowing into the compartment 8 beneath the bag 85 house floor. After the cleaning of the bags, furnace gases are admitted to them from a conduit 9 through the opening controlled by the damper 10 and, when the walls of the bag are again filled with material collected 90 from the furnace gases, the damper 10 is closed and the cleaning operation just described repeated.

The collecting chambers used with my bag cleaning apparatus should be of sufficient capacity and have sufficient opening 95 for the outlet of air in order that there may be no strong currents of air though the collecting chamber while the bag cleaning apparatus is operating.

Having fully described my invention, what I claim as new and desire to secure by Letters Patent of the United States is:

1. Bag cleaning apparatus comprising a flexible tube having a free end adapted to 105 be positioned within a bag to be cleaned, and means for passing air or other fluid through the tube to cause the free end to vibrate and strike the bag.

2. In a bag cleaning apparatus, the combination of a flexible tube having a free end 110 and supported in operative relation with a

bag to be cleaned, and means for forcing air or other fluid through said tube to cause the free end thereof to strike the bag.

3. In a bag cleaning apparatus, the combination of a flexible tube having a free end and supported in operative relation with a bag to be cleaned, means for forcing air or other fluid through said tube to cause the free end thereof to strike the bag, a valve for controlling the supply of air to the tube, and an air reservoir between said valve and the tube.

4. In bag cleaning apparatus, the combination of a bag suspended over a collecting receptacle, a flexible tube having a free end and positioned within the bag, and means for forcing air or other fluid under pressure through said tube to cause the free end thereof to strike the bag.

20 5. In bag cleaning apparatus, the combination of an air reservoir, a bag pervious to

gas and having one end surrounding said reservoir, a flexible tube communicating with the reservoir and having a free end positioned within the bag, and means for supplying air under pressure to said reservoir. 25

6. In bag cleaning apparatus, the combination of an air reservoir, a bag pervious to gas having one end surrounding said reservoir, a flexible tube communicating with the 30 reservoir and having a free end positioned within the bag, a collecting receptacle in communication with the bag, and means for supplying air under pressure to the reservoir.

In testimony whereof, I have hereunto set my hand and affixed my seal in the presence of the two subscribing witnesses.

WILLARD E. PLAYTER. [L. s.]
